MATTRESS PROTECTOR

Isadore Mink, Brooklyn, N. Y.

Application May 9, 1940, Serial No. 334,272

2 Claims. (Cl. 5—354)

This invention relates generally to bed clothing and mattresses and more particularly to novel mattress protectors.

It is well known that mattresses which are more comfortable are usually of a soft and porous nature so that they possess the disadvantage of being difficult to properly clean. This situation is all the more aggravated in connection with mattresses used for infants and mattresses or other bed pads used in hospitals. In order to avoid undesirable soiling of the mattress itself, it has been known to cover the mattress with a water-proof protective sheet, and while various different make-shift methods for keeping the protector in place such as pinning have been utilized in the past, these have been found extremely unsatisfactory. Any means for this purpose utilizing sharp metal objects is of course dangerous and where the means for detachably securing the mattress protector to the mattress is not of an elastic or resilient nature, the protector will wrinkle or crease under the patient or bed occupant, resulting in discomfort, and usually causing the weakening of the material of which the mattress protector is made. This is especially so in the case of coated fabrics in which the water-proof coating is frequently dislodged by sharp creasing with pressure.

Among the objects of the present invention is the provision of a mattress protector which while it performs all the desirable functions of a mattress protector in keeping the mattress clean and protecting it from liquids, still provides a smooth surface upon which the bed occupant may rest in comfort.

Another object herein lies in the provision of mattress protecting structure which by reason of the nature thereof permits of adequate cleansing. In accordance with the present invention mattress protectors may be washed without any unusual precautions being taken in the washing thereof.

Another object of the present invention lies in the provision of a mattress protector in which there is a novel combination of coated or impregnated planar material which is disposed beneath the bed occupant with other planar material being more suited to withstand the abrasion to which certain of the parts of the mattress protector are subjected.

Another object herein lies in the provision of a mattress protecting structure which while conveniently detachably attached to the mattress is nevertheless resiliently maintained in association therewith so that the same may shift to conform

to changes in shape of the mattress caused either by a shifting of the weight of the bed occupant or by reason of the association of the mattress with certain adjustable spring structures such as are found in hospital beds.

Another object herein lies in the provision of a mattress protector having the above described desirable qualities, yet which by reason of the novel arrangement and integration of the parts thereof permits of low-cost, large-scale production; certain of the parts being reenforced without an increase in material or labor.

These objects and other incidental ends and advantages will more fully appear in the progress of this disclosure and be pointed out in the appended claims.

In the accompanying drawing forming a material part hereof, similar reference characters designate corresponding parts throughout the several views in which:

Figure 1 is a view in perspective showing a first embodiment of the present invention in place upon a mattress. Certain of the parts are broken away for purposes of clarity.

Figure 2 is a schematic side elevational view as might be seen from the right side of Figure 1.

Figure 3 is a schematic bottom plan view of Figure 1.

Figure 4 is an enlarged fragmentary detail elevational view showing the manner in which the upper end of the retainer means is integrated with the main protector element.

Figure 5 is a sectional view as seen from the plane 5—5 on Figure 4.

Figure 6 is an enlarged fragmentary sectional view showing a rear portion of the mattress protector as seen from the plane 6—6 on Figure 2.

Figure 7 is a view in perspective showing a modification of the invention.

Figure 8 is a fragmentary enlarged detail view showing the modified structure of Figure 7.

Turning now to the first embodiment of the invention illustrated in Figures 1 to 6 inclusive, the mattress protector generally indicated by numeral 10 includes a main protector element 11 and auxiliary protector elements 12 and 13, and a plurality of retainer means generally indicated by numeral 15 and specifically bearing numerals 16, 17, 18 and 19. The mattress shown in the drawing for the purpose of illustrating the use of the present invention, is indicated generally by numeral 14.

The main protector element 11 is preferably composed of a thin flexible water-proof sheet.

Applicant has found in practice that a sheet com-

posed of a textile fabric woven of rayon threads and impregnated with a flexible regenerated cellulose material is very effective for this purpose. The protector element 10 will of course have the general size and configuration thereof governed by the size of the mattress with which it is to be used, although by reason of the novel construction of the retainer element, the present mattress protector may be used to cover mattresses which vary in size within a certain range. The ends or shorter edges 20 and 21 of the main protector element 11 are suitably secured to the upper edges 22 and 23 of the auxiliary protector elements in any suitable manner, but preferably by rows of stitches 24 and 25.

The longitudinal edges of the now connected main protector element and the auxiliary elements 12 and 13 are each turned inwardly to form the hems 26 and 27. The hems thus formed are provided with slits at the folded portions of the hems, said slits being of a width substantially equal to the width of each of the retainer means 15. The upper ends of each of the retainer means 15 are inserted through said slits and when a double row of stitches is placed in said hem, the said stitches not only secure the hem in place, but also adequately secure the upper ends of said retaining means. The double rows of stitching just referred to are best seen in Figures 1 and 4 and are indicated by numerals 28 and 29. The stitches 28 and 29 may be expeditiously put in place in a single operation by means of a two-needle sewing machine, and the two rows of stitches 28 and 29 preferably extend the entire length of the previously combined main protector element and auxiliary elements.

The lower ends of each of the retainer means 15 are secured to the free edges 30 and 31 of the auxiliary protector elements 12 and 13 respectively. The edges of said auxiliary protector elements being folded upon themselves to form the hems 32 and 33. The hems 32 and 33 are secured in place by means of double rows of stitching 34 and 35, which are similar to the rows of stitching 28 and 29. Since the lower ends of the retainer means 15 are sandwiched between the hems 26 and 27, and 32 and 33, the lower ends of the retainer means 15 are doubly reenforced at the overlapping of said hems which occurs at the points 40 to 43 inclusive, at which there are four thicknesses of the material of which the auxiliary protector elements are composed.

The auxiliary protector elements are preferably composed of woven textile material which possesses high resistance to abrasion as compared to the main protector element 11. This woven textile material is preferably of a relatively soft and flexible nature which allows the auxiliary protector elements to conform properly to the configuration of the mattress adjacent thereto, and also permits the said auxiliary protector elements to conform to and move over the bed spring without becoming damaged.

The retainer means 15 are composed of any suitable resilient material as for example elastic tape, and are capable of stretching longitudinally thereof, this stretching occurring vertically when the protector is in place upon the mattress as seen in Figure 1. The retainer means 15 are of suitable length so that when the mattress protector 10 is placed upon a mattress for use with which it has been designed, the retainer means 15 will exert a sufficient contractive force to maintain the auxiliary protective elements 12 and 13 in proper frictional engagement with the

under surface 45 of the mattress 14. The length of the retainer means will thus be governed by the thickness of the mattress and its compressibility.

5 The operation of the device herein is substantially as follows: In order to place the mattress protector 10 upon the mattress 14, one end thereof, as for example, the end having the seam 25, is slipped over the end 50 of the mattress. The 10 retainer means 17 and 19 being longitudinally extended sufficiently to allow the end 50 of the mattress to be inserted between the opposite portions of the main protector element 11 and the auxiliary protector element 13. The opposite 15 end of the protector element 10 is now passed over the end 60 of the mattress 14 and again the retainer means 16 and 18 are sufficiently extended to allow the auxiliary protector element 12 to pass beneath the lower surface of the end 20 of the mattress 60.

When the mattress protector has been properly placed in association with the mattress, the bed may be made in the usual way by covering the mattress with the usual bed sheets. Vertical 25 pressure placed upon the main protector element 11 and the portions of the mattress 14 which normally carry the body load of a bed occupant, will cause a certain amount of distortion in the main protector element 11 as it conforms to a corresponding distortion in the mattress 14. Tension transversely of the main protector element 11 will be compensated for directly by a slight movement of the auxiliary protector elements 12 and 13 up around the end walls of 30 35 the ends 50 and 60 of the mattress 14. Since the auxiliary protector elements 12 and 13 may not move without displacing the retainer means 15, the said retainer means will also extend themselves to compensate for the last described movement of the auxiliary protector elements 40 12 and 13.

In accordance with the present invention when the mattress protector 10 is in place, the main protector element is always in a taut and smooth condition. When the patient or bed occupant is 45 not lying upon the main protector element, by reason of the action of the retainer means, the main protector element will be drawn into a smooth and flat condition. This characteristic 50 of the present mattress protector is especially useful when the mattress protector is used on a mattress which is placed upon a hospital bed of the type in which the spring platform thereof may be folded, elevated or depressed to various 55 different positions.

For example, when a hospital bed has the head portion of the spring platform thereof raised so that the patient may be placed in a comparatively seated position, there would normally be 60 a tendency for the mattress protector to slide downwardly on the vertical surface of the mattress. This causes a wrinkling of the mattress protector beneath the patient's buttocks and causes a gaping and loosening of the same from 65 the mattress itself at the uppermost head edge of the mattress. If the mattress protector is immovably secured to the upper head edge of the mattress, then under such conditions either the protector itself will tear or the fastening means 70 will pull away from the mattress. In accordance with the present invention however, the retainer means adjacent the head portion of the mattress permits the mattress protector to shift slightly to conform to the altered configuration of the mattress, yet the said retaining means causes 75

a constant tension on the mattress protector which in turn results in a smooth condition of the mattress protector both while the mattress is in a tilted position and after the mattress is returned to the normal flat horizontal position thereof.

It will be noted also in connection with the present invention that the auxiliary protector elements are composed of relatively tough textile material so that said auxiliary protector elements are not easily braided by the relatively rough surface of the spring platform of the bed upon which they rest. It has been found by the applicant that the water-proof sheeting of which the main protector element is composed is best constructed of a relatively thin material which while it may have the desirable water-proof qualities does not possess as much abrasive resistant qualities as is desirable. By the use of a different material for the auxiliary protector elements, the most desirable functions of each of the parts may thus be obtained.

Turning now to the modification of the invention illustrated in Figures 7 and 8, it will be seen that additional secondary retaining means are provided which are attached to the outer longitudinal edges of the main protector element indicated by numeral 11'. Other parts are correspondingly numbered with primed numerals so that further description thereof will not be necessary.

The secondary retainer means, generally indicated by numeral 15' are preferably of a construction similar to the retainer means 15 previously described and are preferably located at the midpoint along each of the longitudinal side edges of the main protector element 11'. The secondary retainer means at the lower ends thereof instead of being attached to the outer corners of the auxiliary protector elements, are detachably attached to some part of the bed or spring frame 100'. The lower ends 101' of the secondary retainer means 15' may be provided with the snap fastener elements including the female snap fastener element 102' and the male fastener element 103'. It is thus a simple matter to detachably attach the lower ends of the secondary retainer means 15' to the bed frame 100'.

In ordinary use, it has been found that the invention does not require the use of the secondary retainer means, but in the case of extremely long beds or other unusual bed structure the use of the secondary retainer means may be desirable.

I wish it to be understood that I do not desire to be limited to the exact details of construction shown and described, for obvious modifications will occur to a person skilled in the art.

5 I claim:

1. As a new article of manufacture, a mattress protector, for use with a mattress, comprising: a main protector element composed of a thin flexible substantially inelastic and water-proof sheet; a pair of auxiliary protector elements connected to the ends of the main protector element, said auxiliary protector elements being composed of woven textile material being substantially inelastic and having high resistance to abrasion; the combined length of the two auxiliary protector elements and the main protector element being longer than the length of said mattress; the auxiliary protector elements being folded under the mattress; the two longitudinal edges of the main protector element and the auxiliary protector elements being turned inwardly upon themselves to form edge hems; and a plurality of elastic retainer means connecting the four longitudinal edges of the auxiliary protector elements to the portions of the said hems on the main protector element lying thereabove.
2. As a new article of manufacture, a mattress protector for use with a mattress on a bed frame comprising: a main protector element composed of a thin flexible substantially inelastic water-proof sheet; a pair of auxiliary protector elements connected to the ends of the main protector element, said auxiliary protector elements being composed of woven textile material being substantially inelastic and having high resistance to abrasion; the combined length of the two auxiliary protector elements and the main protector element being longer than the length of said mattress; the auxiliary protector elements being folded under the mattress; the two longitudinal edges of the main protector element and the auxiliary protector elements being turned inwardly upon themselves to form edge hems; a plurality of elastic retainer means connecting the four longitudinal edges of the auxiliary protector elements to the portions of the said hems on the main protector element lying thereabove; and secondary retainer means attached to the longitudinal side edges of the main protector element, said secondary retainer means being in tape form having a pair of detachable interengaging fastener elements whereby the secondary means may be wrapped about the bed frame and detachably secured to itself.
